ASSEMBLY FOR ELECTRON MICROSCOPES

Frank E. Runge, Haddon Heights, N. J., assignor
to Radio Corporation of America, a corporation
of Delaware

Application April 12, 1944, Serial No. 530,584

6 Claims. (Cl. 250—49.5)

1

The present invention relates to electron microscopes and more particularly to the assembly of the column of which the channel for the electron stream is a part.

In columns of electron microscopes heretofore in use, certain units have been soldered or otherwise permanently secured together and thus internal parts, such as pole pieces, focusing apertures, and other parts requiring repair, replacement or cleaning are accessible only after hours of labor by highly skilled engineers, the latter being necessary by reason of the knowledge required to dismantle the column and reassemble the delicate and intricate parts. Furthermore, difficulty was experienced in maintaining vacuum tight joints because split clamping rings used to secure the gaskets were not entirely reliable. Also, certain joints in the column requiring lateral flexibility for alignment adjustment purposes were equipped with metallic bellows fixedly soldered in place. Such construction was very objectionable because replacement of bellows by even competent service engineers was extremely difficult.

Some of the objects of the present invention are: to provide an improved column assembly of an electron microscope; to provide improved easily removable flexible units as a part of the evacuated channel of an electron microscope; to provide effective sealing of the evacuated channel of an electron microscope, while maintaining the required articulation necessary for proper adjustment; to provide a novel collapsible, self-sealing unit as a portion of the evacuated channel of an electron microscope; to provide means for readily gaining access to the interior of the column of an electron microscope in order to remove, clean and replace pole pieces, apertures, etc.; to provide means for maintaining vacuumtight joints without the use of mechanical fastening means but using instead either weight of the parts, spring pressure or atmospheric pressure, or combinations thereof; and to provide other improvements as will hereinafter appear.

In the accompanying drawings, Figure 1 represents a fragmentary elevation of the column of an electronic microscope embodying the present invention; Figure 2 represents a sectional elevation of the same; Figure 3 represents an elevation of one side of a bellows unit embodying one form of the present invention; Figure 4 represents an elevation of the opposite side of the bellows unit; Figure 5 represents a plan of the unit; Figure 6 represents a section on line 6—6 of Figure 3; Figure 7 represents an enlarged sec-

2

tional elevation of the specimen chamber and contained parts; Figure 8 represents a plan of another form of bellows unit; Figure 9 represents a side elevation of one form of gripping tool for use in removing the bellows unit of Figure 3; and Figure 10 represents a plan of the tool.

Referring to the drawings, the present invention is shown as assembled in association with those parts of an electronic microscope to which the invention relates. The parts thus illustrated are a portion of the column or envelope 9 having an evacuated channel 10 by way of which the cathode ray stream successively traverses the centering apertured member 11, the electronic condensing lens 12, the specimen holder 13, the objective lens 14, the image focusing apertured intermediate viewing screen 15, the projecting lens 16, and finally impinges on the image screen (not shown). The channel 10 leads linearly from the discharge end of the electronic gun 8 to the image screen or photographic area. Since the microscope embodying the present invention differs from the conventional type in that the separate parts are easily disconnectable and include accessible features, instead of parts soldered or otherwise united together and generally inaccessible, without the use of experts and hours of labor, the present description will take these features up in order and thereafter summarize the general assembly.

In order to properly space the objective lens 14 from the projecting lens 16, and also to provide flexibility for axial alignment between them, a flanged tubular section 17 forms a chamber 18, through which a portion of the channel 10 passes. As shown, this portion is formed by a removable flanged housing 20, which includes a window, and a bellows unit 21, the former being seated on the next adjacent lower section 22 of the column 9 through an intermediate gasket 23 to seal hermetically the interior of the sleeve from the exterior, while the latter seats on the housing 20 through a gasket 24 and bears against the next adjacent upper section 25 of the column through a gasket 26 and to be thereby hermetically sealed at both ends.

In order to provide for the quick removal of the bellows unit 21, so that ready access to the pole pieces 19 and 19a may be had for cleaning or other purposes, the unit 21 is of a novel structure comprising two annular heads 33 and 34, spaced apart by a tubular flexible bellows 35, the ends of which seat in and are soldered into the respective heads 33 and 34 as shown in Figs. 3, 4, 5 and 6. The head 33 cooperates with two sockets

36 free to slide laterally in any direction and two centering pins 37, fixed in head 34 and extending parallel to the axis of the head, while the head 34 cooperates with two like sockets 38 and two centering pins 40, also parallel to the axis of the head. Entering the sockets and encircling the respective pins are coil springs 41 under compression to exert a relatively heavy repelling pressure of one head with respect to the other. This pressure serves to compress the gaskets 24 and 26 and effect a complete sealing action.

For manually compressing the heads 33 and 34 against the action of the springs 41, to shorten the unit for convenient removal, the head 33 is provided with four bearing pins 42, 43, 44 and 45, projecting in pairs from opposite sides of the head and transversely aligned. The pin 42 rides in a slot 46 of a lever 47; the pin 43 rides in a slot 48 of a lever 50; the pin 44 rides in a slot 51 of a lever 52; and the pin 45 rides in a slot 53 of a lever 54. Likewise, the head 34 is provided with four bearing pins 55, 56, 57 and 58, projecting pairs from opposite sides of the head and transversely aligned with each other and with the pins of the head 33. The pin 55 rides in a slot 60 of the lever 50; the pin 56 rides in a slot 61 of the lever 47; the pin 57 rides in a slot 62 of the lever 52; and the pin 58 rides in a slot 63 of the lever 54. The two levers 47 and 50 are relatively movable about a common pivot 64, and the two levers 52 and 54 are relatively movable about a common pivot 65, so that the two pairs of levers form a balanced lazy-tongs structure arranged to be operated by pinching two rods 66 and 67 towards each other. The rod 66 has its ends respectively pivotally connected to the projecting short arms 68 and 69 of the respective levers 50 and 52, while the rod 67 has its ends respectively pivotally connected to the projecting short arms 70 and 70' of the respective levers 47 and 54. It should be noted that the respective bearing pins and the bars are properly held in assembled condition by spring washers 71. All these movable joints are very loosely fitted to permit flexibility of the entire assembly.

As a means for engaging, compressing and removing the unit 21 from the chamber 18, a novel tool has been devised comprising, in the present instance, a U-shaped member forming a handle 72 at one end and two spaced jaws 73 at the other end. The associated member of the tool comprises a strip having a handle 74 at one end and a jaw 75 at the other end, this strip being pivoted at 76 to the other member of the tool. In closed position, one part of the tool lies within, or in the plane of, the other to form a compact unit. The jaws 73 are respectively provided with curved seats 77, laterally in register and positioned to function in the opposite direction to a like seat 78 on the jaw 75. As shown, the curvature of the three seats is complementary to the contour of the rods 66 and 67. The length of the jaws and the radius of swing is such that the seats of the bifurcated member can engage one side of one of the rods 66 or 67 while the seat of the other member can engage the opposite side of the other rod. When so positioned, squeezing together of the handles causes the jaws to draw the rods 66 and 67 towards each other and to thereby retract the heads 33 and 34, sufficiently to permit the bellows unit to be removed through aligned doorways formed respectively in the inner electro-static shield 80 and the outer electro-static shield 80a for the wall of the section 17. A door 79 is mounted to slide circumferentially about the

shield 80a to open and close the doorway to the chamber 18, and is provided with a viewing aperture 81. It will thus be evident when the vacuum in the channel 10 is broken that the door 5 79 can be opened, the tool inserted and the bellows unit 21 removed. With this latter removed, the column 9 is accessible for the purpose of removal and replacement of pole pieces, apertures, and associated parts.

10 In connection with the section 17, it should be noted that a plurality of equally spaced thumbscrews 103 (here shown as four), are adjustably mounted to cooperate respectively with flat surfaces on the periphery of the adjacent section 25, and hence manipulation of these screws serves as a means to align the pole pieces in the objective and projecting coils.

15 In order to provide for the desired lateral flexibility of the column between the condenser and objective coils, the chamber 82, in which the specimen holder 13 is located, is formed by a tubular flanged coupling 83 which seats upon the upper end of the frame 25 in which the coils 84 are located as a part of the objective lens 14. A gasket 85 is interposed between the coupling 83 and the frame 25 and serves as a seal under the weight of the coupling and atmospheric pressure. The upper end of the coupling member 83 is of larger internal diameter to receive an annular sealing unit, which forms a part of the channel 10 and, in the present instance, comprises a tubular bellows 86 mounted between two heads 87 and 88. A coiled spring 89 encircles the bellows 86 and seats at opposite ends respectively against the heads 87 and 88. The head 87 seats on member 30 83 through a sealing gasket 90, the assembling being such that the bellows 86 is aligned with and forms a part of the column channel 10. The head 35 88 seats against the next adjacent annular frame 91, in which the coils 92 of the condensing lens 12 are located. A gasket 93 is interposed between the head 88 and the frame 91 for sealing purposes. A ring 94 encircles the head 88 as an alignment guide and is removably fastened to the frame 91.

40 45 Thus it will be seen that the sealing unit is freely mounted between the member 83 and the frame 91, being held by the weight of the frame 91, and hermetically sealed by the compressed bellows 86 and spring 89, and the exterior atmospheric pressure. The removal of the sealing unit is easily made because it is not soldered or otherwise fixed in place, and consequently when the vacuum is broken, the condenser coil and parts above may be lifted off and the unit removed without tools. One side wall of the member 83 is provided with an access hole arranged to be closed by a plug type closure 95 having a flange 96 to seat against a gasket 97 and be held sealed by atmospheric pressure when the column is evacuated.

60 50 To provide for lateral flexibility of the column including the electron gun 8, an annular member 98 is seated upon condenser lens 12. A frame 106, which supports the gun section 100, is mounted for lateral movement on the annular member 98.

65 60 A gasket 101 hermetically seals the joint between the member 98 and the lens 12, by reason of the weight of the member 8 and associated members plus atmospheric pressure. A like gasket 102 is disposed between the member 98 and the 70 gun section 100, and seals the joint therebetween in the same manner. The lower end portion of the member 98 encircles the centering aperture member 104, and includes a window 103 for viewing the inclined face of the member 104, said face being coated with a fluorescent material.

A sight opening 105 is registered with the window 103, and is formed in an outer surrounding frame 106, which is a part of an adjustment structure not here necessary to be described, as it is fully disclosed and claimed in my earlier Patent No. 2,418,817, granted April 1, 1947. A sealing unit 107 is interposed between the gun section 100 and the annular member 98, and is similar to the sealing unit heretofore described in that it is formed of annular heads spaced apart by a bellows 101 and hermetically sealing the column by atmospheric pressure and the pressure of the compressed bellows and spring acting against end sealing gaskets. This unit is likewise freely mounted in the column so that not only is flexible lateral adjustment possible but also ready removal of the unit when the column is to be taken apart.

From the foregoing it will be apparent that the column forming the channel to be evacuated consists of a plurality of disconnectable sections arranged in superposed relation and hermetically sealed with respect to each other. Certain of the sections serve as frames for the coils of the electronic lenses, while others respectively provide chambers in which parts of the column are formed by bellows units which contribute to easy adjustment, since each bellows unit is capable of lateral deflection as well as axial or endwise movement. One of the chambers serves to receive the specimen and its holder, while others contain respectively the adjustable apertures for focusing the stream of electrons.

In connection with the chamber between the objective lens and the projection lens, it should be noted that by breaking the vacuum in the channel 10, the door 79 and the outer member including the aperture 81 can be opened, allowing access to the bellows unit 21. The tool can now be inserted to bring the jaws 73 and 75 respectively into gripping relation with the rods 66 and 67, whereupon the unit 21 can be squeezed together and removed. With this unit out of the way, flanged housing 20, the aperture member 15 and pole pieces 19 and 19a can be removed for cleaning or other purposes.

It will now be apparent that a complete unitary column assembly has been devised wherein collapsible, self-sealing units form parts of the evacuated channel and which are so arranged and assembled as to be held in leak-proof relation under all operating conditions. These units are not attached to adjacent parts by soldering or other fastening means, but are maintained solely by weight of adjacent parts plus atmospheric pressure. With the present novel construction the column becomes a single, elongated, articulated chamber, certain essential portions thereof adjacent the pole pieces being readily accessible in a minimum of time and by unskilled workmen. Furthermore, by taking advantage of atmospheric pressure all joints are automatically held tight and leak-proof. Also, by providing a special tong the collapsible units can be reached and quickly removed in order to expose the pole pieces, and focusing apertures for removal.

I claim as my invention:

1. In an electron microscope, a column portion formed by electron lens sections and an interme-

iate section forming a chamber, said intermediate section having an access opening and a door for said opening, a bellows unit in said intermediate chamber and forming a portion of the electron channel of said column, and means accessible through said opening for collapsing said unit for removal.

2. In an electron microscope, a column portion formed by electron lens sections and an intermediate section forming a chamber, said intermediate section having an access opening and a door for said opening, a bellows unit in said intermediate chamber and forming a portion of the electron channel of said column, means accessible through said opening for collapsing said unit for removal, and means for hermetically sealing the joints between the respective ends of said unit and adjacent parts.

3. A bellows unit for the column of an electron microscope comprising a pair of annular heads, a tubular flexible bellows between said heads, spring means normally repelling one head with respect to the other, and manually operable means for squeezing said heads toward each other to reduce the length of the unit for removal and replacement from the column.

4. A bellows unit for the column of an electron microscope comprising a pair of annular heads, a tubular flexible bellows between said heads, and levers forming a pair of lazy tongs for manually squeezing said heads towards each other to reduce the length of the unit for removal and replacement from the column.

35 5. In an electron microscope, the combination of a tubular column formed by a plurality of aligned sections, at least one of which is a bellows unit comprising two annular heads, a tubular bellows between said heads, coil springs normally repelling one head with respect to the other, and accessible manually operable means in said columns for squeezing said heads towards each other to reduce the length of the unit for removal from said column.

removal from said column.

6. In an electron microscope, the combination
45 of a tubular column formed by a plurality of
aligned sections, at least one of which is a bellows unit comprising two annular heads, a tubular bellows between said heads, coil springs nor-
mally repelling one head with respect to the
50 other, manually operable means in said column
for squeezing said heads towards each other for
removal from said column, and a casing about
said column having a door controlled opening
55 registered with said bellows unit for access to said
squeezing means.
